(57) **CLAIM**

The ornamental design for a purse hook, as shown and described.

DESCRIPTION

FIG. 1 is a perspective view of a purse hook showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top perspective of the purse hook, shown in condition of use; and,

FIG. 9 is another top perspective of the purse hook shown in condition of use.

The broken lines showing environment is for illustrative purposes only and forms no part of the claimed design.
